DESIGN FOR A TONE ARM

Lloyd J. Andres, Itasca, Ill., assignor to Fidelitone
Incorporated, Chicago, Ill., a corporation of Illinois

Application April 23, 1947, Serial No. 138,569

Term of patent 14 years

(Cl. D26—14)

To all whom it may concern:

Be it known that I, Lloyd J. Andres, a citizen of the United States and resident of Itasca, in the county of DuPage and State of Illinois, have invented a new, original, and ornamental Design for Tone Arm, of which the following is a specification, reference being had to the accompanying drawing, forming part thereof.

Fig. 1 is a top plan view of a tone arm, showing my new design.

Fig. 2 is a side elevational view of Fig. 1.

Fig. 3 is a left-hand end view of Fig. 1.

The characteristic features of my design reside in the portions shown by means of full lines in the drawing.

I claim:

The ornamental design for a tone arm, substantially as shown and described.

LLOYD J. ANDRES.
